UNITED STATES PATENT OFFICE

EDGAR BOYD KAY, OF WASHINGTON, DISTRICT OF COLUMBIA; FLORENCE MEANS KAY
EXECUTRIX OF SAID EDGAR BOYD KAY, DECEASED

FURNACE

Application filed September 1, 1928. Serial No. 303,534.

This invention relates to improvements in furnaces, and more particularly to means whereby a furnace may be stoked, or the ashes withdrawn without affecting the draft of the 5 furnace or admitting such an amount of cold air into the fire chamber as will lower the temperature thereof.

An object of this invention is to provide a simple, durable and inexpensive arrangement of parts that may be applied to any of the usual types of furnaces previously constructed or be built into the furnace originally.

A further object is to provide a structure 15 wherein the stroking of the furnace may be effectively accomplished without the use of any of the complicated forms of shaker grate bars, consisting of rocking or tilting members subject to a high rate of failure, are expensive and difficult to replace.

For purposes of illustration a preferred form of the invention is shown it being understood that slight changes in form and minor details of construction may be resorted 25 to without departing from the spirit of the invention.

Similar numerals indicate corresponding parts in all the figures of the drawings in which:

30 Fig. 1 is a longitudinal vertical section through the furnace.

Fig. 2 is a similar enlarged view of a portion of the same.

Fig. 3 is a front view of the parts shown 35 in Fig. 2.

Fig. 4 is a horizontal section of these parts taken directly above the movable dead plate.

While this invention may be applied to any form of furnace, it is particularly designed for use in high temperature combustion units such as incinerators and the drawings show its application to same.

By reference to the drawings by numerals, 1 indicates the front wall of the incinerator, 45 2 the main fuel feed and stoking door frame and 3 the ash pit door frame.

The fire chamber is shown at 4, and 5 indicates a portion of a grate made up of any preferred form of stationary grate bars, provided with draft passages.

The grate is slightly inclined downwardly toward the front of the furnace, and rests on a cross beam 6. Said beam 6 also supports the inner edge of a dead plate frame 7 to which it is secured in such a position as to bring the upper face of said frame flush with the upper face of the grate and form a continuation thereof.

The forward edge 8 of the dead plate frame is mounted in any preferred manner on the inner face of the main stoking door frame 2.

When applying this invention to the usual form of furnace when forced draft is not to be used, no partition in the ash pit is required, but in the structure shown as applied to a high temperature incinerator, a partition 9 is arranged across the ash pit, beneath the forward end of the grate and rear edge of the dead plate frame.

The partition 9 is provided with an opening 10 and closure doors 11, adapted when desired to entirely separate the ash pit into rear portion 12, located beneath the grate 5 and the forward portion 13 beneath the dead plate.

As stated above, partition 9 and associated parts are not necessary when the usual induced draft is practiced, but in the form of furnace shown, forced draft may be supplied to the rear portion 12 of the ash pit in any preferred manner, such as through flues arranged in the side walls of the ash pit as shown at 14, provided with louvres 15 controlling the flow of air into said chamber 12. Said flow of air may be supplied from any 80 source and be led under control to chamber 12 in any preferred manner.

The movable dead plate 16 in the form shown in the drawings is pivotally mounted at 17 and is adapted to snugly fit opening 18 in the frame 7. Said plate being provided on its under side with depending lugs 19 supporting a rod to which is secured the inner end of a link 20 extending out through the front of the incinerator, the outer end of link 20 is pivotally mounted on operating arm 21, provided at its upper end with a socket 22, into which an operating lever 23 is adapted to be inserted to operate the movable dead plate in an obvious manner.

- To permit link 20 to operate through a small opening in front of the incinerator, the lower end of operating arm 21 is connected at 24 to one end of a toggle link 25, the other 5 end of said toggle link being mounted in a lug 26, projecting from the face of the furnace. Toggle link 25, provides a shiftable pivotal point for the operating arm 21, which permits the link 20 to traverse an opening 10 in the front of the furnace practically the same size as the cross section of the link 20, as the operating arm 21 and link 20 are operated to swing the dead plate 16 from open to closed position.
- 15 Frame 2 is provided with guides 27 between which the main stoking and fuel door 28 of a sliding guillotine type operates, said door being counter-balanced in the usual manner by a weight suspended by cable running over a pulley (not shown).

- The main stoking or fuel door preferably operates on a slight incline, to provide as nearly as possible an air tight joint between the door and frame.
- 25 Arranged in the main door 28 is a stoke hole 29, through which the proper implement (not shown) may be introduced for the purpose of stoking the furnace. This consists of disturbing the material being burnt on the 30 grates and causing the ashes and other non-combustible ash and residue, the finer particles passing down through the grates, and the coarser being dragged out on the dead plate.

- The stoke hole is closed by a gravity door 35 or cover 30, preferably pivotally mounted on pins 31 passing through lugs 32 and 33 mounted on the main door and stoke hole cover respectively.

- This cover as shown rests by gravity 40 against the face of the main door and to increase the pressure and provide an air tight joint between said parts, the cover is weighted as shown at 34. A lug in which one end of an operating ring 36 is secured, provides means 45 for opening and closing the stoke hole cover, which remains in either its open or closed position, due to the manner of mounting the same.

- In operation, air forced into the furnace, is 50 heated during its passage through the flues on its way to the rear of the ash pit, owing to the location of the air flues 14 at the sides of the ash pit, as shown.

- To prevent a blast of cold air entering beneath the grate when the ash pit doors are 55 opened and permit cleaning out the forward portion of the ash pit without diminishing the temperature of same, the doors 11 covering opening 10 in the partition 9 are provided 60 to entirely segregate the rear portion of the ash pit from the forward portion.

- To prevent an objectionable amount of cold air reaching the fire chamber while stoking, the stoke hole in the main door is provided, 65 and to permit depositing the non-combustible

material stoked from the fire grates, into a chamber from which it may be removed, without diminishing the temperature either above or below the grates, the movable dead plate is provided.

In view of the above it will be obvious to one familiar with the operation of incinerators, that the material to be destroyed is deposited on the grate through an opening 50 directly above the fire grate. On said grate 75 the garbage or other refuse is consumed. There is however a part of said material which when consumed leaves a comparatively small quantity of fine ash that readily passes down through the grate bars when the fire is 80 stoked. On the other hand there is more or less incombustible substances such as tin cans, rocks and the like that necessarily remain on the grate and must be stoked off and disposed of, and it is such material that may, by inserting the proper implement through the stoke hole, be stoked forward and pulled downwardly from the grate on to the movable dead plate, from which it may be dropped into the front portion of the ash pit for 90 wardly of partition 9. Such material may be removed from the ash pit without lowering the temperature above or below the grate. When the firing up period is completed, and a reduction of temperature in the furnace is 95 not objectionable, doors 11 may be opened and the rear portion of the ash pit cleaned out.

Having fully described my invention what I claim and desire to secure by Letters Patent is:

1. In an incinerator or the like, provided with a wall, a grate, a fire chamber arranged above the grate and having a doorway arranged in said wall, said chamber having an opening in its top through which material to be incinerated is deposited on the grate, a main stoking door normally closing said doorway, an ash pit arranged below the grate, a movable dead plate arranged between the grate and main stoking door, said grate being inclined downwardly toward said dead plate, a second pit arranged below the dead plate, a partition segregating the ash pit from the second pit along the line where the front end of the grate meets the dead plate, registering doorways for the ash pit and second pit arranged respectively in said partition and said wall, doors normally closing said doorways, and means for operating the dead plate to discharge materials from the latter into the second pit.

2. In an incinerator or the like, a grate, a fire chamber arranged above the grate and provided with a main stoking door, said chamber having an opening in its top through which material to be incinerated is deposited on the grate, an ash pit arranged below the grate and provided with a doorway, a movable dead plate arranged between the grate 125 and the doorway, and means for operating the dead plate to discharge materials from the latter into the ash pit.

- and the stoking door and adapted to receive materials stoked from the grate, said grate being inclined downwardly toward said dead plate, a second pit arranged below the dead plate, a second pit arranged below the dead plate and provided with a door, movable doors cooperating with said doorway for segregating the ash pit from the second pit along the line where the front end of the grate meets the dead plate, means for introducing air under pressure into the ash pit, and means for operating said dead plate for discharging materials from the latter into the second pit. 5 the dead plate and grate, an air draft flue leading to the ash pit, and means for actuating the dead plate from the exterior of the housing for discharging materials from the dead plate into the ash pit.
- EDGAR BOYD KAY. 70
- 75
3. In an incinerator or the like, a grate, a fire chamber arranged above the grate and provided with a main stoking door, said chamber having an opening in its top through which material to be incinerated is deposited on the grate, a movable dead plate arranged between the grate and the stoking door and adapted to receive materials stoked from the grate, said grate being inclined downwardly toward said dead plate, an ash pit arranged beneath the grate, a second pit arranged beneath the dead plate, a partition arranged along the line where the front end of the grate meets the dead plate separating the second pit from the ash pit and provided with an opening, doors normally closing the opening for segregating each pit from the other, a door closed doorway for the second pit, and means for operating the dead plate for discharging materials from the latter into the second pit. 20 25 30 35 40 45 50 55 60 65
- 80 85 90 95 100 105 110 115 120 125 130
4. In an incinerator or the like, a grate, a fire chamber arranged above the grate, an ash pit arranged below the grate, a forced draft flue leading to the ash pit, a second pit arranged at one side of the ash pit, means including a door sealing the second pit from the ash pit and arranged along the line of the front end of the grate, a door for the second pit registering with the last mentioned door, and means for discharging materials from the fire chamber into the second pit. 45
5. In a forced draft incinerator, a housing having a wall provided with a doorway, a grate within the housing and having its front edge terminating at the inner surface of said wall, a movable dead plate arranged in the wall at one edge of the grate and forming a portion of the bottom of the doorway, a main stoking door closing said doorway, a fire chamber arranged in the housing above the dead plate and grate, a hatch in the housing above the grate for use in dropping the material to be burned into the fire chamber, a smaller doorway in the main stoking door to permit the introduction of a stoking tool into the fire chamber and the removal of said tool from the chamber to allow manual stoking and depositing of material from the grate on to the dead plate without interfering materially with a high temperature to be maintained in the fire chamber, a door for the smaller doorway, an ash pit arranged beneath
